LIPSTICK HOLDER

August Mitchell, New York, N. Y., assignor to
 Scovill Manufacturing Company, Waterbury,
 Conn., a corporation of Connecticut

Application September 20, 1934, Serial No. 744,754

8 Claims. (Cl. 206—56)

This invention relates to lipstick holders.

It is the principal object of the present invention to provide an improved lipstick holder that is simple in construction and one that 5 can be produced at relatively low cost.

With these general objects and others in view, the invention consists in the features, combinations, details of construction and arrangements of parts which will first be described in connection with the accompanying drawing and then 10 more particularly pointed out.

In the drawing:

Fig. 1 is a view in side elevation of a lipstick holder constructed in accordance with the present 15 invention, showing the holder closed;

Fig. 2 is a front view, with parts broken away, showing the holder open and the lipstick advanced for use;

Fig. 3 is a similar view with part of the casing and other parts removed and parts broken away;

Fig. 4 is a rear view with another part of the casing and other parts removed;

Fig. 5 is a view similar to Fig. 3, showing the 25 lipstick withdrawn and the holder closed;

Fig. 6 is a sectional view taken on the line 6—6 of Fig. 3 but showing all the casing and other parts in place;

Fig. 7 is a sectional view taken on the broken 30 line 7—7 of Fig. 3 but showing the removed parts in place; and

Fig. 8 is a top end view showing the holder closed.

Referring to the drawing, there is provided 35 a two-part casing or housing divided longitudinally and capacitated to be secured together by the mere act of assembly without the need of extraneous fastening devices or operations. In the embodiment here shown as an example, the housing or casing comprises an open-faced box-like section, which may be termed the rear section, having a rear wall 11, side walls 12, 13, bottom 14 and curved top 15. The other part 40 of the housing, which may be termed the front section, is an oppositely disposed open-faced box-like section having a front wall 16, side walls 17, 18, and bottom 19 and curved top 20. The side walls and bottom of the second housing 45 section have their edge portions offset to telescope over the sides and bottom of the first housing section (Figs. 1 and 8).

The curved tops of the two housing sections are cut away to give the assembled housing a 50 rectangular discharge opening 21 (Figs. 1 and 8),

In order to secure the two housing sections together by the mere act of assembly, one of the housing sections, for example the front section, has a plurality of locking nibs 22 struck in from the metal of each of the overlapping 5 side walls. As appears more clearly in Fig. 1, the upper and lower nibs are arranged in reversely faced pairs, the locking shoulders 23 facing sideways. Intermediate the ends is a single nib with its shoulder faced downward. 10 These nibs are received by suitable locking holes cut in the side walls of the other housing section. It will be understood that the nibs shown in Fig. 1 are duplicated on the other side. After the internal parts, later described, have 15 been inserted, the casing sections are brought together with the edges of the front section overlapping the edges of the rear section. As this is done, nibs 22 snap into the complementary locking holes and the casing parts are automatically 20 secured together by the act of assembly.

Slidable in the housing is a carrier cup 25 for a lipstick 26. The carrier is actuated, in the embodiment here shown as an example, by a thumb-piece 27 extending through a slot 28 25 in the front wall of the housing. This thumb-piece is formed as a fold in a metal piece 29 having two fingers or prongs 30 which take into holes 31 in the carrier cup. The outside edge of the thumb-piece is preferably knurled to provide a proper gripping surface. The construction described provides an inexpensive thumb-piece that is connected to the carrier by the mere act of assembly. As will be apparent from Fig. 7, once the casing sections are assembled, 35 this actuating element is retained in place by the casing, the slot 28 being wide enough to pass the thumb-piece 27 only.

The invention in its entirety comprises a 40 flexible strip moving with the carrier and arranged to cover the discharge opening when the lipstick is withdrawn and to expose the opening upon advance of the carrier, to permit the lipstick to be moved out to a position for use. As here shown as an example, one end of a flexible 45 strip 33 carries a pin or dowel 34 which takes into a suitable hole in the carrier cup, thus connecting the parts by the mere act of assembly. As will be apparent from Fig. 5, once the casing is assembled, this dowel 34 is held in place by the 50 wall of the casing. As appears more clearly in Figs. 3 and 6, the pin 34 serves an additional function in that it acts as a stop for the lipstick when the holder is loaded.

When the lipstick is withdrawn into the hold- 55

er, the free end of strip 33 covers the discharge opening and so serves as an end closure for the housing. As the thumb-piece is moved up in its slot to advance the lipstick, the free end of the strip is withdrawn to expose or open the discharge orifice by the time the tip of the lipstick reaches the same. Upon reverse movement of the thumb-piece, the lipstick is withdrawn and the free end of the strip again moves 10 into a position covering the discharge opening.

There is provided guide means for the lipstick carrier and the flexible strip. As here shown as an example, seated flat against the inside rear face of the rear housing member is a 15 plate 35 having a portion offset to form a panel 36 with rounded upper and lower ends. Similarly seated in the front housing member is a plate 37 having a portion offset to form a similar panel 38. In the bottom of the housing is an 20 arcuate guide piece 39 positioned and supported by legs 40. The flexible strip is guided at the sides and top between the edges of panels 36, 38, and the adjacent walls of the housing and at the bottom between the lower curved edges of the 25 panels and guide piece 39.

The carrier cup 25 is confined and guided between the opposing faces of the panels 36, 38, and is prevented from wobbling by a lug 42 struck up from the rear of the cup and sliding 30 in a slot 43 formed in panel 36 of plate 35.

Panel 38 of plate 37 has two slots 44 to accommodate the fingers 30 of the actuating element. As these slots 44 straddle slot 28 in the casing, the latter is backed by plate 37 (Fig. 2). That 35 is, plate 37 closes slot 28 and prevents or tends to prevent the entrance of dust and dirt.

The invention in its entirety includes means for tending to retain the carrier in withdrawn position against accidental dislodgment. In the 40 embodiment here shown as an example, panel 36 has two spring nibs or tongues 45 which bear against the carrier cup in withdrawn position to hold the same firmly in such position except when advanced by the thumb-piece.

Plates 35 and 37 are secured in place by the mere act of assembly without the necessity for extraneous fastening. Edgewise movement of the 45 plates is prevented by their fit within the respective casing sections and right line movement is prevented by the interposition of the lipstick carrier which serves in the nature of a spacer (Fig. 6). The guide piece 39 is similarly secured in place without extraneous fastening. It is prevented from endwise movement by its fit 50 between the walls of the casing (Figs. 3 and 5), and from edgewise movement by its fit between plates 35, 37 (Fig. 6).

It will be understood that the various parts may be assembled in the two casing sections as 55 may be found convenient, the assembly of these two sections being the final step that secures all the parts.

With the construction described, not only are all the parts secured in position by the mere act 60 of assembly, but the casing sections, the plates, the actuator and the guiding insert may be formed from stampings, thus making for economy of production.

What is claimed is:

70 1. A lipstick holder comprising a two-part casting divided longitudinally and including two open-faced box-like sections, the edges of one section telescoping over the edges of the other section, complementary locking elements carried 75 by the respective sections for automatically

effecting a locking together of the two sections upon telescoping assembly thereof, the two sections being cut away at one end to form a discharge opening, a lipstick carrier movable in the casing, and an actuating element located outside the casing and connected with said carrier for operating the same, one of the casing sections having a slot for the passage of said connection. 5

2. A lipstick holder comprising a two-part casting divided longitudinally and including two 10 open-faced box-like sections, the edges of one of said casing sections telescoping over the edges of the other casing section, locking nibs on the overlapping portions of one of said sections, the other section having complementary holes to 15 receive said nibs, said casing sections being cut away at one end to form a discharge opening, a lipstick carrier movable in the casing, and an actuating element located outside the casing and connected with said carrier for operating the same, one of the casing sections having a slot 20 for the passage of said connection.

3. A lipstick holder comprising a two-part casting divided longitudinally and including two 25 open-faced box-like sections, the edges of one of said casing sections telescoping over the edges of the other casing sections, locking nibs on the overlapping portions of one of said sections, the other section having complementary holes to 30 receive said nibs, said casing sections being cut away at one end to form a discharge opening, a unit 35 movable in the casing and including a lipstick carrier and a flexible strip connected therewith, said strip being arranged to cover the discharge opening when the carrier is withdrawn and to expose the opening when the carrier is advanced, and an actuating element located outside the casing and connected with said unit for operating the same, one of said casing sections having a slot 40 for the passage of said connection.

4. A lipstick holder comprising a two-part box-like casing having a rounded upper end provided with a discharge opening, a unit movable in said casing and including a carrier for a lipstick and a flexible strip connected thereto, 45 said strip being arranged to cover said opening when the carrier is withdrawn and to expose the opening when the carrier is advanced, a pair of plates fitting freely in the respective sections of said casing and embossed with inwardly extending panels having rounded upper and lower ends, the upper rounded end of the casing and the upper edges of said panels constituting a guideway for said flexible strip, and arcuate guide surface complementary to the lower edges 50 of said panels for providing a guideway therebetween for said strip, and an actuating element for the carrier and strip located outside the casing and connected with said carrier to operate the same, the casing and one of said 55 plates having slots for the passage of said connection.

5. A lipstick holder comprising a two-part box-like casing having a rounded upper end provided with a discharge opening, a unit movable 60 in said casing and including a carrier for a lipstick and a flexible strip connected thereto, said strip being arranged to cover said opening when the carrier is withdrawn and to expose the opening when the carrier is advanced, a pair 65 of plates fitting freely in the respective sections of said casing and embossed with inwardly extending panels having rounded upper and lower ends, an insert fitting freely in the lower end of the casing and comprising an arcuate guide 70 75

- portion and two positioning legs, the upper rounded end of the casing and the guide portion of said insert forming guideways for the strip with the respective upper and lower edges of said panels, and an actuating element for the carrier and strip located outside the casing and connected with said carrier to operate the same, the casing and one of said plates having slots for the passage of said connection.
- 10 6. A lipstick holder comprising a two-part box-like casing having a rounded upper end provided with a discharge opening, a unit movable in said casing and including a carrier for a lipstick and a flexible strip connected thereto, said strip being arranged to cover said opening when the carrier is withdrawn and to expose the opening when the carrier is advanced, a pair of plates fitting freely in the respective sections of said casing and embossed with inwardly extending panels having rounded upper and lower ends, the upper rounded end of the casing and the upper edges of said panels constituting a guideway for said flexible strip, an arcuate guide surface complementary to the lower edges of said panels for providing a guideway therebetween for said strip, an actuating element for the carrier and strip located outside the casing and connected with said carrier to operate the same, the casing and one of said plates having slots for the passage of said connection, and an inwardly extending spring tongue on the lower end of one of said plates for engaging the carrier in its withdrawn position and tending to retain it in such position.
- 25 7. A lipstick holder comprising a casing having a discharge opening in one end, a unit movable in said casing and including a lipstick car-
- rier and a flexible strip connected thereto, said strip being arranged to cover said opening when the carrier is withdrawn and to expose the opening when the carrier is advanced, an actuating member located outside the casing and connected with said unit for operating the same, the casing having a slot for said connection, two opposing surfaces between which said carrier slides, at least one of said surfaces having an inwardly extending spring tongue for engaging the carrier in its withdrawn position and tending to retain it in such position.
- 30 8. A lipstick holder comprising a two-part casing divided longitudinally and including two open-faced box-like sections, the edges of one section telescoping over the edges of the other section, complementary locking elements carried by the respective sections for automatically effecting a locking together of the two sections upon telescoping assembly thereof, the two sections being cut away at one end to form a discharge opening, a lipstick carrier movable in the casing, an actuating element located outside the casing and connected with said carrier for operating the same, one of the casing sections having a slot for the passage of said connection, a pair of plates fitting freely in the respective sections of said casing and embossed with inwardly extending panels having rounded upper and lower ends, the upper rounded end of the casing and the upper edges of said panels constituting a guideway for said flexible strip, and an arcuate guide surface complementary to the lower edges of said panels for providing a guideway therebetween for said strip.

AUGUST MITCHELL.
